SHOE STITCHER

Eugene G. Wolf, St. Louis, Mo., assignor to Landis
Machine Company, St. Louis, Mo., a corpora-
tion of Missouri

Application February 26, 1940, Serial No. 320,845

9 Claims. (Cl. 112—57)

The invention relates to sewing machines and more particularly to machines for stitching leather, and the present drawings illustrate and the specification describes a machine of the well-known Goodyear type adapted for stitching shoe soles and uppers together and equipped with the present invention.

In stitchers of the class referred to, the thread passes from the spool through a tension device, then through a thread measuring device, then through a thread lock, then over an auxiliary take-up device, then over a main take-up device, and then to the thread looper which lays the thread around the needle to be drawn through the work. During each cycle of operations the thread measurer draws through the thread tension (the thread lock being set) sufficient thread for the next stitch. Also during each cycle of operations, the main take-up moves towards the work to give up slack so the needle may draw the thread through the work without undue tension. Thereafter the main take-up moves in the opposite direction to pull on the thread and tighten the stitch just formed and also to pull through the thread lock (temporarily released) the supply of thread for the next stitch which supply the thread measurer has just drawn through the tension device.

While the main take-up is giving up slack, it is necessary to provide some tension on the thread to hold it to the thread hook and the looper and prevent the thread loop from being so loose as to be unmanageable. The auxiliary take-up is provided for this purpose and may consist of a spring mounted roller over which the thread passes on its way from the thread lock to the main take-up device.

Throughout all of a sewing operation, except during the initial stitching, there is a portion of each cycle of the machine during which the thread lock is set, and the machine presser foot and the work support clamp the work and the previously set stitches, and the auxiliary take-up takes up the slack in the stretch of thread between the work and the thread lock. Then, when the main take-up functions, the thread tensioned thereby first pulls the auxiliary take-up to a fixed, stop-engaging position and then pulls the stitch-forming portion of the thread against the work to tighten the stitch. Then, as the main take-up gives up slack, it releases the auxiliary take-up which is moved by its spring to maintain the desired reduced tension upon the thread so that the thread will be held against the thread hook and the barb of the needle.

But at the beginning of a sewing operation, and prior to the insertion of the work into the machine, the operator manually rotates the main shaft by its hand wheel to place the main take-up in a position where its initial movement, after the machine is started, will be to give up slack. In so setting the main take up, there is no great tension on the thread and the auxiliary take-up spring is not distorted and hence the auxiliary take-up is projected to the end of its ordinary take-up movement. Hence, when the machine starts to stitch and the main take-up moves up to give up slack, the auxiliary take-up does not immediately perform its normal function of keeping the thread taut between the thread lock and the needle and there is a surplus of thread at the work. This surplus is not reduced by the initial downward movement of the main take-up because the thread measurer has functioned to supply as much thread as is necessary for a complete stitch and this supply is added to the original length of thread between the thread lock and the work. The initial surplus is absorbed by the cumulative looseness of the first few stitches but it is only thereafter that the auxiliary take-up is pulled down and is spring actuated to maintain the thread taut as intended. As a result, the thread near the hook and needle may be slack throughout the first few stitching operations and the first few stitches will not be set tightly in the work but will stand out from the work, presenting an unsightly appearance.

The main object of the present invention is to avoid this ineffective setting of the first few stitches of each sewing operation.

This object has been attained in previous machines by the use of a cam and lever for positively holding the auxiliary take-up from maximum take-up position during the initial action of the machine. This requires additional mechanism in the restricted space available for the necessary cams, levers, etc.

It is a further object of the present invention to control the auxiliary take-up as described above by a simple connection to another part of the mechanism, such as the thread measurer, for example, which will function without requiring a separate cam and lever arrangement which adds to the complexity of the mechanism and increases the difficulty of access to adjacent parts.

These objectives are attained by the structure illustrated in the accompanying drawings in which—

Figure 1 is a side elevation of a stitcher of the class described equipped with the present inven-

tion and shows the main take-up arm during its downward movement away from the work but before it has reached the end of such movement.

Figure 2 is a similar view of the more essential parts of the mechanism drawn to an enlarged scale and shows the main take-up arm at the end of its downward movement.

Figure 3 is a detail vertical section on the line 3—3 of Figure 2.

The machine frame 1 mounts the usual head 2 with upright standards 3 journaling the main cam shaft 4. The main take-up cam groove 5 receives a roller 6 on one end of a lever 7 pivoted at 8 and connected at its opposite end 9 by a link 10 to the short arm 11 of a bell crank pivoted at 12, the opposite end of the other arm 13 of the bell crank forming the main take-up arm which carries the roller 14.

The thread measurer cam groove 15 receives a roller 16 on the end of the arm 17 of a bell crank pivoted at 18 and having a depending arm 19 connected by a link 20 to a slide 21 pivoted at 22 to a harp-like frame 23 which is connected at 24 to the presser foot lever 25, whereby the height of frame 23 is controlled by the height of the presser foot 31. Variations in the height of frame 23 vary the height of slide pivot 22 and this varies the throw of a block 26 slidable in slide 21 and connected to an arm 27 on a shaft 28 which also mounts an arm 29 carrying a grooved thread measuring roller 30.

In each cycle of operations of the machine, roller 30 is raised from the position shown in Figure 1 to that shown in Figure 2, the exact extent of the rise depending upon the height of frame 23 as determined by the thickness of the work between the work support 36 and the presser foot 31.

A thread locking lever 31 is timed to press against the thread on a stationary guide roller 32 when thread measuring roller 30 is moved upwardly, whereby roller 30 draws thread through a thread tension device 33 from the supply spool (not shown) and not from the portion of thread extending from roller 30 to the work. Locking lever 31 is actuated by a crank 34 on a shaft 35 which is oscillated by a cam (not shown) in the usual manner.

All of the above described main take-up, thread feeding and thread measuring devices are well known and in themselves do not constitute the present invention.

An auxiliary take-up arm 40 is pivoted on the machine frame at 41 and carries a roller 42 at its outer end. A spring 43 has its left hand end held down by the thread lock crank shaft 35 and passes over a grooved roller 52 on the thread measurer crank shaft 28 and beneath a stud 45 at the outer end of auxiliary take-up arm 40. The spring tends to thrust arm 40 upwardly to the position shown in Figure 2 but thread measurer arm 29 carries a hook 50 overlying spring 43 and when arm 29 is moved downwardly by the action of cam 15 on bell crank 17—19, hook 50 engages spring 43 and holds it to the position shown in Figure 1.

Thread T passes from lock roller 32 over auxiliary take-up roller 42, then over roller 14 on main take-up arm 13, then up to the thread looper 51 and then to the thread hook 46. The needle 47 engages the thread between looper 51 and hook 46 in the usual manner.

Bell crank 17—19 moves thread measuring arm 29, and hook 50, downwardly during the lowermost inch or so of the travel of main take-

up arm 13 and this is the position to which the main take-up arm must be moved by the operator when he begins a sewing operation. Hence, it is obvious that because of hook 50 the auxiliary take-up actuating spring 43 cannot move auxiliary take-up arm 40 upwardly at such a time.

When the operator begins a sewing operation, he depresses a foot treadle to raise presser foot 31 and rotates the main shaft by the hand wheel until the main take-up is in its lowermost position. Thread lock 31 and thread tension 33 are released by the same treadle movement which released the presser foot and the operator draws thread freely through the machine to overlie the work support 36. The operator then inserts the work between the presser foot and work support 36 and in line with the path of the needle and awl. The operator then releases the treadle, permitting the presser foot to clamp the work and the thread together and to the work support and also permitting the thread lock to set.

Then the machine is started and the main take-up moves upwardly from the position shown in Figure 2 to give up slack, and the thread measurer roll 30, behind the closed thread lock, is raised by cam 15, crank 17—19, link 20, arm 27, crank 28 and arm 29 to measure off additional thread for the next stitch. Upon the subsequent downward movement of the main take-up, the thread lock is released and the additional thread just measured is added to the length of thread between the thread lock and the work, and the surplus thread, due to the initial giving up slack by the main take-up, still exists except insofar as it had been decreased by the looseness of the initial stitch.

But with the present structure, at the time the operator rotated the main shaft by the hand wheel to place the main take-up in down position, hook 50 held down the auxiliary take-up spring during the clamping of the work and the setting of the thread lock (by the release of the treadle), and the subsequent movement upwardly of hook 50 and the ensuing action of the auxiliary take-up spring permits the latter to move auxiliary take-up roll 42 to take up surplus thread resulting from the giving up of slack by the main take-up. Hence the initial stitch is taut. Hence the first few stitches of each sewing operation will be drawn as tightly as any subsequent stitches.

While the auxiliary take-up 40—42 will be held down by hook 50 during a portion of each subsequent stitch, as during portions of the initial stitches as just described, this holding down will not affect the operation of the machine and the action of hook 50 will be immaterial until the next sewing operation is begun.

The present invention is characterized by the temporary interruption of the pull of the auxiliary take-up on the thread leading to the needle during a restricted portion of the cycle of operation of the machine, thereby making it possible for the auxiliary take-up to function effectively immediately subsequent to said cycle portion, which it could not do during the first few stitches of each sewing operation except for the restraint, by means other than the pull of the thread, on the auxiliary take-up roller. Preferably, but not necessarily, the restraint is of a positive nature and is exerted by a thread manipulating device of the machine, thereby eliminating the necessity of additional cams, followers, levers and connections.

The details of the device may be varied with-

out departing from the spirit of the invention and the exclusive use of such modifications as come within the scope of the claims is contemplated.

What is claimed is:

1. In a stitching machine of the class described, a main take-up, a thread measurer, and an auxiliary take-up device including a spring thrusting the thread engaging portion of the auxiliary take-up device in one direction, there being a connection between said thread measurer and said device for checking the action of said spring during a portion only of the cycle of operation of said thread measurer.
  2. In a stitching machine of the class described, a main take-up, a thread lock, a thread measurer, means for setting said lock as said measurer draws thread from the supply and for releasing said lock when said measurer gives up the thread it has so drawn, an auxiliary take-up, and means for holding said auxiliary take-up against tensioning the thread when said thread measurer gives up thread.
  3. In a stitching machine of the class described, a main take-up moving to give up slack to the needle, an auxiliary take-up moving to keep the thread taut against the needle as said main take-up gives up slack, and a thread measurer moving to draw thread from a supply as said main and auxiliary take-ups move as described and then moving to yield the thread so drawn to said main take-up and simultaneously moving said auxiliary take-up to non-functioning position.
  4. In a stitching machine of the class described, a main take-up, a thread measurer, and an auxiliary take-up device including a spring thrusting the thread engaging portion of the auxiliary take-up device in one direction, said spring extending past a portion of said thread measurer and being engaged by an element on said thread measurer during a portion of the cycle of operation of said thread measurer so as to prevent said auxiliary take-up device from functioning.
  5. In a stitching machine of the class described, a main take-up, a thread measuring device in-
  - 10
  - 15
  - 20
  - 25
  - 30
  - 35
  - 40
  - 45
- cluding an oscillating shaft and an arm thereon the outer end of which reciprocates to measure the thread, a thread lock including an oscillating shaft adjacent to said thread measuring device shaft, and an auxiliary take-up including a leaf spring having one end underlying said thread lock shaft and its intermediate portion overlying said thread measuring device shaft and thereby being distorted and its outer end moving the thread engaging portion of the auxiliary take-up, there being a hook on a reciprocating portion of the thread measurer for distorting said spring and rendering the same ineffective during a portion of the stitching cycle.
6. In a stitching machine of the class described, a thread tension device, a thread lock, a main take-up, an auxiliary take up engaging the thread between said main take-up and said lock, and a thread manipulating device between said thread tension device and said thread lock and controlling the operation of said auxiliary take-up.
7. In a stitching machine of the class described, a main take-up, an auxiliary take-up, and a thread drawing device including an element engaging said auxiliary take-up, when said device is moved in one direction, to render said auxiliary take-up inoperative during a portion only of the cycle of operation of the machine.
8. In a stitching machine of the class described, a thread main take-up, a thread auxiliary take-up device including a thread-engaging element and an actuating spring therefor functioning to keep the thread taut, a thread pulling device moved positively in one direction and including an element movable therewith and engaging said device to hold its spring against action during a portion only of the cycle of operation of the machine.
9. In a stitching machine of the class described, a main take-up, an auxiliary take-up, a thread measurer and an element movable with said measurer as the latter releases thread to the take-ups to temporarily render said auxiliary take-up inoperative.

EUGENE G. WOLF.
